UNITED STATES PATENT OFFICE.

JOHN F. W. ERDMANN, OF PHILADELPHIA, PENNSYLVANIA.

IMPROVEMENT IN CUTTER-HEADS.

Specification forming part of Letters Patent No. **140,905**, dated July 15, 1873; application filed October 5, 1872.

To all whom it may concern:

Be it known that I, JOHN F. W. ERDMANN, of Philadelphia, in the county of Philadelphia and State of Pennsylvania, have invented new and valuable Improvements in Cutter-Heads; and I do hereby declare that the following is a full, clear, and exact description of the construction and operation of the same, reference being had to the annexed drawings making a part of this specification, and to the letters and figures of reference marked thereon.

Figure 1 of the drawings is a perspective representation of a cutter constructed with my improvements. Fig. 2 is a bottom view of the same. Fig. 3 is an elevation of one of the plates.

The improvements herein described have reference to that class of machines used for making cabinet moldings. The improvement consists in the combination, with a rotary cutter-head having thin feather-edged bits, of elastic cushions arranged between the head and said bits, as and for the purpose herein-after described.

In the accompanying drawing I have shown a cutter-head made according to this improved construction.

A shows the head, which is of cast metal, of which the wings *a* form a part; *a'* being a central hole, through which the shaft passes. B are the cutter-plates slotted at *b b*. C C are

oblong iron plates secured to the outside of the cutters by means of screws *c* passing through the head. Back of each of the cutters is a flat piece of India rubber, *e*, on which said cutters rest, and through which the screws *c* pass. The screws *c* fit in the slots *b b*, already mentioned, so that when it is desired to take off the cutters to sharpen them the screws may be loosened and the cutters drawn from between the plates C and cushion *e* or wings *a*.

The India-rubber cushion forms an elastic seat for the cutters, and allows them to "give" to a considerable extent, which I have found of advantage in operating; but where it is not deemed desirable to use this cushion it may be dispensed with.

What I claim as my invention, and desire to secure by Letters Patent, is—

The combination, with the bit B constructed from a thin plate of steel furnished with a feather cutting-edge, of the rotary cutter-head A and elastic cushion *e*, arranged substantially as and for the purpose described.

In testimony that I claim the above, I have hereunto subscribed my name in the presence of two witnesses.

JOHN F. W. ERDMANN.
